UNITED STATES PATENT OFFICE.

HAMILTON LINDSAY, OF CLEVELAND, OHIO, ASSIGNOR TO THE LINDSAY WIRE WEAVING COMPANY, OF CLEVELAND, OHIO, A CORPORATION OF OHIO.

LAY-RETAINING DEVICE.

1,365,417.

Specification of Letters Patent. Patented Jan. 11, 1921.

Application filed July 12, 1920. Serial No. 395,807.

To all whom it may concern:

Be it known that I, HAMILTON LINDSAY, a citizen of the United States, residing at Cleveland, in the county of Cuyahoga and State of Ohio, have invented a certain new and useful Improvement in Lay-Retaining Devices, of which the following is a full, clear, and exact description, reference being had to the accompanying drawings.

- 10 This invention relates to improvements in looms for weaving wire cloth, particularly to the type of loom set forth in my prior Patent 1,052,929. In weaving wire cloth on the shuttle loom it has been found that the 15 middle of the lay or batten had a tendency to vibrate when very wide cloth is being woven. This vibration continues while the shuttle is passing from one shuttle box to the other and it throws the shuttle from its 20 path and consequently disturbs the alignment of the warp thread.

The object of my invention is to provide means which will prevent the vibration of the lay while the shuttle is passing from one 25 shuttle box to another. Other objects include the provision of a means which may be positioned on the frame of a machine and adapted to retain the center of the lay during the time in which the shuttle is moving 30 across the machine and to instantly release it thereafter.

The above and other objects will be hereinafter more fully set forth in the following description which relates to the accompanying drawings. The essential characteristics are set forth in the claims.

In the drawings Figure 1 is a front elevation of a loom embodying the features of my invention; Fig. 2 is a cross section 40 through the center of the loom; Fig. 3 is a large view of the mechanism shown in Fig. 2 comprising the retaining device; Figs. 4 and 5 are details of the parts of the mechanism adapted to be used with the retaining 45 device.

Designating the parts by the use of reference characters, in the drawings, 10 represents the standards which with the cross rail 11, comprise the frame of a wire weaving 50 loom, having a customary warp beam 12, guide roll 13, and cloth beam 14. Depending from the top of the frame and pivotally connected thereto is the batten 15, which carries the lay 16; while positioned at both 55 sides of the frame are the shuttle boxes 17,

and the corresponding picker arms 18. This mechanism is set forth in the aforementioned patent. My present invention, pertains to the means for retaining the center of the lay in a rigid position while 60 the shuttle is passing between the ranks from one side of the machine to the other.

Looms have heretofore been provided with mechanisms for preventing the vibration of the batten, where narrow cloth is 65 woven, but on wider machines the middle of the lay also has considerable vibration, which results in throwing the shuttle off its track, or course, as it travels from one shuttle box to the other.

The batten is arranged to swing about a pivoted connection at the top of the frame. As shown in Fig. 2, the batten 15 is in the rearward position and engaged by a pawl 20. This pawl is pivotally connected at 19 70 to a bracket 27 and is operated by a rock shaft 22 through a rock arm 21 and a connecting link 23, whereby a rocking motion of the rock shaft imparts a similar motion to the pawl. Suitable cam mechanism, not 75 shown, operates the rock shaft 22 to so position the pawl 20 that the finger 30 may engage the center of the lay. Continuous engagement with the lay would rapidly wear 80 the metal away, so I have provided a removable block 32 with an engaging tooth 31 which may be hardened and tempered. The 85 pawl is so mounted that when the lay swings upwardly and rearwardly, the engaging tooth will cause the end of the latch to hook 90 over the tooth and to retain the lay.

A bracket 27 may be rigidly secured to the cross rail 11 and be adapted to carry a removable buffer plate 29 in addition to the pawl 20. The buffer plate serves to take 95 up the shock of the lay when it is arrested in its rearward movement. The buffer plate may be any flexible material such as rubber or fiber which may be changed when the impact surface is worn. The rock shaft 22 100 extends across the frame and is supported by bearings positioned on the cross rail 11. This shaft, corresponding to the rock shaft 35 shown in my prior Patent No. 1,002,163, is operated by mechanism described and 105 claimed therein. The position of the rock arm 21 with relation to the rock shaft may be adjusted by a set screw 26, and the movement of the pawl 20 with relation to the rock shaft may be regulated by altering the posi- 110

tion of the rock arm 21, and the length of the connecting link 23. The connecting link is preferably a rod having yokes or bifurcated members at each end; the upper end 5 thereof, being connected to the rock arm and the lower end to the pawl.

In operation, the position of the rock arm, connecting link, and pawl, with relation to the rock shaft is such, that the pawl at the 10 center of the machine is synchronized with the retaining devices at both ends of the machine. In other words, when the cam mechanism operates the rock shaft 22 to release the retaining devices at the ends of 15 the lay, then the rock arm 21 is also moved and the pawl 20 is caused to move with it. Assuming that the lay has imparted a final blow to the wire cloth and is striking the buffer plate, then the machine is timed, so 20 that the pawl will engage the hardened tooth and retain the lay against the buffer plate, thereby preventing vibration.

It will be seen from the foregoing description that I have provided a mechanism 25 which will effectively prevent vibration at the center of the lay and that this mechanism is adapted to be attached to and co-ordinate with existing wire weaving looms.

Having thus described my invention I 30 claim:

1. In a loom, the combination with a frame of a lay means for engaging the lay intermediate the ends thereof and adapted to hold it at the end of its rearward swing.
2. In a loom, the combination with a frame, of a lay means for operating the lay, a latch mechanism intermediate the ends of the lay and adapted to engage and steady it at the end of its rearward swing.
3. In a loom, the combination with a frame of a lay means for operating the lay, a latch mechanism pivotally mounted on the frame intermediate the ends of the lay and adapted to hold it at the end of its rearward swing.
4. In a loom, the combination with a frame of a lay means for operating the lay, a latch mechanism near the middle of the lay and means for engaging and disengaging the 50 said mechanism independently of the lay operating means.
5. In a loom, the combination with a lay,

of a member intermediate its ends and carried thereby, a latch operable independently of the lay, and adapted to cooperate with 55 the said member, and means for engaging and disengaging the latch, whereby the lay may be momentarily held at the end of its rearward swing.

6. In a loom, the combination with a 60 frame of a lay, a latch carried by the frame, and adapted to engage the center portion of the lay when it is at the end of its rearward swing, and to momentarily hold it, and means for operating the latch.

7. In a loom, the combination with a frame of a lay, a fixed member carried thereby, a fixed support on the loom frame, a latch pivotally mounted on the fixed support and adapted to engage the said member intermediate the ends of the lay, means for operating the latch, and means for absorbing the impact of the lay at the end of its rearward swing.

8. In a loom, the combination with a 75 frame of a lay, an engaging block secured substantially at the center of the lay, a support on the frame, a member mounted thereon and adapted to engage said block whereby vibration of the lay may be prevented 80 when it is near the end of its rearward swing.

9. In a loom, the combination with a frame of a lay, a latch pivotally mounted on 85 the frame and adapted to engage the lay intermediate the ends thereof, a rock shaft, means connecting the rock shaft with the latch, and means for operating the rock shaft whereby the latch will be disengaged.

10. In a loom, the combination with a 90 frame of a lay, a fixed support on the frame, a latch pivotally mounted on the said support and adapted to engage the center of the lay, a buffer plate on the said support adapted to retard the rearward motion of the lay, 95 a rock shaft supported on the frame, a rock arm associated with the said rock shaft, a link connecting the rock arm with the latch, and means for operating the rock shaft whereby the latch will engage and disengage the lay.

In testimony whereof, I hereunto affix my signature.

HAMILTON LINDSAY.
